ATTORNEY

UNITED STATES PATENT OFFICE.

HARRY PERLMUTTER, OF BROOKLYN, NEW YORK.

BABY-CARRIAGE.

1,351,439.

Specification of Letters Patent. Patented Aug. 31, 1920.

Application filed November 20, 1918. Serial No. 263,424.

To all whom it may concern:

Be it known that I, HARRY PERLMUTTER, a citizen of the United States, residing at Brooklyn, in the county of Kings and State of New York, have invented certain new and useful Improvements in Baby-Carriages, of which the following is a specification.

This invention relates to improvements in baby carriages and has for its object to provide a carriage seat having entirely within the lines of the body a movable bottom with a back-rest hinged thereto in such relation that when the bottom is moved to one position the back-rest is disposed at an angle to the movable bottom, and when the bottom is in another position the back-rest lies in a plane parallel to that of the bottom member.

Another object is to provide a form of connection between the sliding bottom and the hinged back-rest whereby when the back-rest is in its inclined relation to the bottom, the parts are held in such relation against accidental displacement.

Other objects and aims of the invention, more or less broad than those stated above, together with the advantages inherent, will be in part obvious and in part specifically referred to in the course of the following description of the elements, combinations, arrangements of parts, and applications of principles constituting the invention; and the scope of protection contemplated will appear from the claims.

In the accompanying drawing, which is to be taken as part of this specification, and in which I have shown a merely preferred form of embodiment of the invention, Figure 1 is a plan view of the carriage body provided with my invention; Fig. 2 is a sectional view on the line 2—2 of Fig. 1; and Fig. 3 is a view similar to Fig. 2, showing in full lines the relation of parts when the back-rest is in position parallel to the bottom so that the back-rest and the bottom constitute substantially a continuous surface and showing in dotted lines another position of the parts.

Referring to the numerals on the drawing, there is indicated at 4 the body of a baby carriage, which may be provided in the bottom with a well 5 to accommodate the feet of the child in the sitting position. Horizontally disposed along the inner walls of the body near the bottom are horizontal slide-ways 6, in which is guided for horizontal sliding movement a bottom slide 7. These slide-ways 6 may comprise grooved members

and the bottom slide 7 may be provided with tenons along its edges engaging in the grooves. The sliding member 7 is capable of two positions, one being shown in Fig. 2 and the other in Fig. 3 in full lines. In the Fig. 2 position the child is supposed to sit on the sliding member 7 and the opening into the well 5 is left exposed for the accommodation of the feet of the child. In the Fig. 3 position the sliding member 7 has been moved forwardly or to the left to cover up the well 5.

The numeral 8 indicates a back member which is hinged to the rear end or edge of the sliding member 7, the hinge being indicated at 9. This back-rest 8 may comprise an integral length of wire which is bent into the form of a frame, U-shaped in general and having the ends of the legs of the U turned toward each other to engage in the straps 11 of the hinge. On this frame is fixed a facing 12. The back-rest is connected to fixed portions of the carriage body at each side of the sliding member adjacent the bottom by means of links, a link 14 being pivoted as indicated at 15, and a link 16 being pivoted to the back-rest as indicated at 17, and the links 14 and 16 being pivoted together as indicated at 18, a stop member 19 being secured to one of the links 14 or 16, or to the pivot 18, to prevent movement of the back-rest toward the sliding member 7 beyond a certain extent, as for instance the relation shown in Fig. 2. In Fig. 2 the back-rest is in proper position to support the back of the child, while in Fig. 3 the slide has been moved forwardly to cover up the well 5. The slide may be provided with a loop of leather or cloth at its forward edge to be engaged by the fingers in pulling the slide to its Fig. 3 position and in moving it back to its Fig. 2 position. When the slide is to be pulled forward from the Fig. 2 position to the Fig. 3 position the pivot 18 must be raised up, so that the slide will be free to move to the Fig. 3 position while the links will assume the full line position of Fig. 3 and the back-rest will also assume the full line position of Fig. 3 so that it comes substantially parallel to the sliding member 7 and constitutes a rearward extension thereof. In this position of the parts the carriage may be used as a bed in which the child may lie at length. As shown in the drawing the hinges 9 are so disposed that in the Fig. 3 position of the parts the back-rest and the

sliding member are not in the same plane, although they are parallel. It will be obvious that by lowering the eyes of the hinges 9 it will be possible to bring the sliding 5 member and the back-rest into the same horizontal plane. This however is not important because when the carriage is to be used as a bed the entire bottom is covered with bedding which takes up any slight inequalities of surface. I consider it important however that the links should be provided for controlling the back-rest, and that these links should be provided with the stop 19, which prevent movement of the back-rest 10 toward the sliding member beyond a certain point; and it is also important that when the parts are in what may be called the sitting position of Fig. 2, the slide cannot move forwardly until the pivots 18 between 15 the links are lifted up. Movement of the slide forwardly of the guard is of course limited by the edge of the slide coming in contact with a front bottom wall 20, while a back bottom wall 21 supports the rear end 20 of the back-rest when the latter is in the horizontal position of Fig. 3. While I have spoken of only two positions of the back-rest, that is the respective full line positions 25 of Figs. 2 and 3, intermediate positions are 30 possible if desired, one such intermediate position being indicated by the dotted lines of Fig. 3, dotted lines at 22 indicating the corresponding position of the sliding member 7. It will be evident also that the control 35 of the device may be exercised by manipulation of the back-rest instead of by manipulation of the sliding member, though the latter is preferable as putting less strain on the link connections.

10 Inasmuch as many changes could be made in the above construction, and many apparently widely different embodiments of my invention could be made without departing from the scope thereof, it is intended 45 that all matter contained in the above description or shown in the accompanying drawings shall be interpreted as illustrative and not in a limiting sense.

It is also to be understood that the language 50 used in the following claims is intended to cover all the generic and specific features of the scope of the invention and

all statements of the scope of the invention which, as a matter of language, might be said to fall therebetween.

55

I claim:

1. A carriage body having a sliding seat with a drop-back hinged thereto, and link connections between the drop-back and fixed portions of the carriage body, the latter being forward of the hinged connection and between the back and seat, all of the parts being within the carriage body.

60

2. A carriage body having a sliding seat with a drop-back hinged thereto, and link connections between the drop-back and fixed portions of the carriage body, all of the parts being within the carriage body, said link connections being forward of the hinged connection and between the back and seat and provided with means for preventing movement of the drop-back toward the 65 sliding member beyond a certain point.

70

3. A carriage body having a sliding seat with a drop-back hinged thereto, and link connections being forward of the hinged connection and between the drop-back and fixed portions of the carriage body, all of the parts being within the carriage body, said link connections when the drop-back is 75 80 in one position preventing movement of the sliding member toward the front of the carriage.

4. A device as set forth in claim 1 in which the drop-back comprises a frame 85 made of an integral length of wire bent into U-shape with the ends of the legs of the U turned in toward each other and engaged in hinge eyes secured to the sliding member.

5. A carriage body having a sliding seat 90 with a drop-back hinged thereto, and link connections being forward of the hinged connection and between the drop-back and fixed portions of the carriage body, all of the parts being within the carriage body, a 95 carriage body provided with a stop body for limiting movement of the sliding member toward the front of the carriage and also with a member for supporting the outer end of the drop-back when the latter is in 100 its horizontal position.

In testimony whereof I affix my signature.

HARRY PERLMUTTER.
